UNITED STATES PATENT OFFICE.

ARCHIBALD B. HEATH, OF LYNBROOK, NEW YORK.

DESIGN FOR A LAMP.

Application filed April 20, 1925. Serial No. 13,172. Term of patent 14 years.

To all whom it may concern:

Be it known that I, ARCHIBALD B. HEATH, my new design.
a citizen of the United States, residing at Lynbrook, in the county of Nassau and State of New York, have invented a new, original, and ornamental Design for Lamps, of which the following is a specification, reference being had to the accompanying drawing, forming part thereof.

Figure 1 is a front perspective view of Figure 2 is a three-quarter front perspective of the same.

I claim:

The ornamental design for a lamp, as shown.

ARCHIBALD B. HEATH.
